UNITED STATES PATENT OFFICE.

EARL A. HECHT, OF MANSFIELD, OHIO.

DESIGN FOR A TIRE TREAD.

Application filed December 1, 1921. Serial No. 519,294. Term of patent 14 years.

To all whom it may concern:

Be it known that I, EARL A. HECHT, residing at Mansfield, in the county of Richland and State of Ohio, a citizen of the United States of America, have invented a new, original, and ornamental Design for a Tire Tread, of which the following is a specification, reference being had to the accompanying drawing, forming a part thereof, wherein—

Fig. 1 is a partial plan, and Fig. 2 is a transverse section of a tire having the new tread design.

I claim:

The ornamental design for a tire tread as shown.

EARL A. HECHT.

In the presence of—

JOHN H. COSS,
RUTH SNYDER.
